UNITED STATES PATENT OFFICE.

WILLIAM KANE, OF PHILADELPHIA, PENNSYLVANIA.

BOILER STRUCTURE.

1,231,375.

Specification of Letters Patent. Patented June 26, 1917.

Application filed November 24, 1916. Serial No. 133,240.

To all whom it may concern:

Be it known that I, WILLIAM KANE, a citizen of the United States, residing at Philadelphia, in the county of Philadelphia and State of Pennsylvania, have invented 5 certain new and useful Improvements in Boiler Structures, of which the following is a specification.

My invention consists of an improved 10 boiler structure, one object being to provide a boiler structure which may include one or more independent boilers.

Another object of my invention is to provide a sectional base or support for the 15 boilers which can be readily varied so that the number of boilers may be increased or decreased according to requirements.

A further object is to provide a sectional top or hood in which the sections may be 20 taken from or added to according to the number of boilers employed.

A still further object is to so construct 25 my invention that each boiler may be heated by a separate gas burner and that the several parts may be easily and quickly cleaned.

Another object is to so design my improved boiler structure that it will be neat and compact and can be manufactured and sold at a reasonable cost.

30 These objects, and other advantageous ends which will be described hereinafter, I attain in the following manner, reference being had to the accompanying drawings in which—

35 Figure 1 is a top plan view of my invention with the hood removed and including two independent boilers.

Fig. 2 is a front elevation of Fig. 1 showing the hood thereon.

40 Fig. 3 is a plan view of Fig. 2.

Fig. 4 is a side view of Fig. 2.

Fig. 5 is a perspective view of one of my improved boilers.

Fig. 6 is a detached perspective view of 45 two of the hood sections shown in Figs. 2 and 3.

Figs. 7 and 8 are respectively front and top views of one type of boiler-supporting plate which I employ.

50 Figs. 9 and 10 are front and top views of another type of boiler-supporting plate which I also use when two or more boilers are included in the structure.

Fig. 11 is a front elevation of my invention including one boiler.

Referring to Figs. 1 to 10 of the draw-

ings, 1 represents the base or boiler-support which has end sections 2 and 3. These sections are preferably made of cast metal and have angularly disposed surfaces 4 and 5 60 provided with recesses 6 and 7, preferably at their bottom edges.

Each of these side plates has a ledge 8 projecting inwardly from their inner surfaces, and a portion of the web of these 65 plates extend upwardly a short distance from said ledges 8 as illustrated at 9 in Figs. 1 and 2.

When two or more boilers, as shown at 10 and 11, are included in the structure, 70 front and rear plates 12 and 13 are connected to the end section 3. The plates 12 and 13 are substantially similar with the exception that the plate 12 has a large opening 14, while the plate 13 has a comparatively small opening or recess 15.

Each of the plates 12 and 13 has an offset extension or flange 16 which engages the inner surface of the respective portions 17 and 18 of the end section 3, and bolts 19 80 and 20 extend through the extensions 16 and the portions 17 and 18 to thus secure the plates 12 and 13 to the end sections and so that the outer surfaces of the plates 12 and 13 are flush with the outer surfaces of 85 the portions 17 and 18. Furthermore, each of the plates 12 and 13 has a ledge 21 which is of the same height as the ledges 8 of the end sections 2 and 3.

Each of the plates 12 and 13 has an extension 22 which extends beyond a rib 23, the latter being formed on the inner surface thereof. These extensions 22 are flush with the outer surface of the respective plates 12 and 13. Other boiler supporting plates 90 24 and 25 are positioned respectively at the front and rear and are included in the base 95 1. These plates 24 and 25 are of substantially similar construction with the exception that the plate 24 has a large opening 100 26 while the plate 25 has a comparatively small recess or opening 27.

Furthermore, each of the plates 24 and 25 have off-set extensions 28 and 29 at opposite sides, said extensions being substantially the 105 same as illustrated in Figs. 5 and 6. The extension 29 is designed to engage the inner surface of the extension 22 on the plates 12 and 13 and bolts 30 pass through the extensions 29 and 22 and thereby secure the 110 front plates 12 and 24 and the rear plates 13 and 25 together.

The extensions 28 on the plates 24 and 25 engage the inner surfaces of front and rear portions 31 and 32 of the end section 2, and bolts 33 and 34 secure said extensions 28 to the end section 2, so that the outer surfaces of the portions 31 and 32 are substantially flush with the outer surfaces of the plates 24 and 25.

Each of the plates 24 and 25 has an inwardly projecting flange 35 which forms a ledge below the upper edges of said plates, and the ledges 35 are on the same level with the ledges 21 and 8 of the plates 12 and 13 and end sections 2 and 3. These ledges 15 form a support for the boilers 10 and 11 and the ledges 8 also form a support for side panels 36 and 37. These side panels adjacent their upper ends have outwardly projecting flanges 38 and 39 upon which rest end sections 40 and 41 of a hood 42, said latter sections also having internal ribs 43 and 44 which rest upon the upper surfaces 45 and 46 of the boilers 10 and 11.

The hood sections 40 and 41 are similarly constructed and are interchangeable. Each of these sections is provided with lugs or ears 47 which are designed to be bolted to lugs or ears 48 on a central hood section 49. Furthermore, each of the sections 40 and 41 has a semi-circular opening 50, and these semi-circular openings 50 are designed to register with semi-circular openings 51 at opposite edges of the central sections 49 to provide holes for the outlet pipes 52 and 53 from the boilers 10 and 11.

In addition, the central hood section 49 has a flanged opening 54 to which may be connected a pipe to carry off the products of combustion in a manner hereinafter more fully described.

Each of the sections 40 and 41 has a longitudinally extending lip 55 which extends from its semi-circular opening 50 to one edge as clearly shown in Fig. 4. These lips are 45 designed to engage under the top of the central section 49 from the semi-circular openings 51 to one outer edge of the central hood 49. The central hood section 49 is also provided with longitudinally extending lips 56 50 designed to engage under the end hood sections 40 and 41, and when the hood sections are connected together, these lips 56 will be in line with the lips 55 and are therefore oppositely disposed from the openings 50 and 51 as clearly shown in Figs. 3 and 4. By this construction the same pattern may be used to cast both of the end hood sections 40 and 41, and when these hood sections are joined together, the under-lying lips 55 and 56 will form a seal for the partings between the end sections 40 and 41 and the central section 49, said parting being interrupted only at the openings through which the pipes 52 and 53 extend.

The boilers 10 and 11 are of similar con-

struction and are made of hollow castings having lateral extensions 57 on opposite sides thereof which are spaced apart to provide flues 58. The end extensions 57 on one side of each boiler are longer than the intermediate extensions 57 as shown at 57^a and include tongues 59, and at the opposite side the end extensions 57^a are provided with grooves 60 designed to receive the tongues 59 when two of the boilers are 70 placed adjacent as illustrated in Fig. 2, thus forming an interlock for the boilers and also forming a seal to prevent the products of combustion from laterally passing out of the central flues 58 through the parting between the boilers 10 and 11. By having the intermediate extensions 57 shorter than the end extensions 57^a, additional flue space 58^a is provided as clearly shown in Fig. 1.

The flues 58 extend from top to bottom 85 of the boilers 10 and 11 and communicate with the chamber 61 provided by the hood 42 and the space provided by the base 1. Gas or other hydro-carbon burners (not shown) may be inserted through the openings 14 and 26 of the plates 12 and 24 respectively and are preferably placed directly below the boilers 10 and 11. Doors 62 and 63 are provided to form a partial closure for the openings 14 and 26 of said plates 12 and 90 24. The products of combustion pass upwardly through the flues 58 into the chamber 61, and then outwardly through the opening 54.

When only one boiler is used, as shown in 100 Fig. 11, I dispense with the plates 12 and 13 and secure the extensions 28 and 29 of the plates 24 and 25 directly to the end sections 2 and 3, since it will be noted that as above described, the extensions 28 and 29 are similar and are off-set. The hood may be made in two sections as shown at 64 and 65, having portions which provide an outlet 66 for the products of combustion and registering semi-circular openings 67 for the outlet 110 pipe 52.

If it is desired to provide a structure including three or more boilers, a plate 12 and a plate 13 is added for each additional boiler, it merely being necessary to disconnect the bolts 19 and 20 and to move the end sections 3 away from the plates 12 and 13 to permit the insertion of two other plates 12 and 13 which are connected respectively to the end sections 3 and to the first-mentioned 120 plates 12 and 13.

It will thus be noted that any number of boilers may be provided which are in no way connected to each other within the boiler structure, so that they are free to expand 125 without injury to any of the other parts. It will be noted that as the boilers are increased in number, the hood sections may be increased in number either by providing additional central sections 49 or in forming sepa- 130

rate sections without the additional flue openings 54.

By my improved invention, I do away with the connecting of boilers or boiler units by coupling nipples as heretofore was customary, since it is well known in the art that different boilers or boiler units expand in different manners, and the coupling nipples heretofore employed often became loosened or fractured, thus injuring the structure. Therefore, with my invention I provide a boiler structure in which each of the boilers is independent of other boilers in the construction, but have a unitary mounting which may be readily varied to permit other boilers to be added thereto or taken therefrom.

Each of the boilers in the present instance is provided with an inlet opening 68 for return steam or water and in the several drawings I have illustrated these openings as being located adjacent the bottom portion and in the back of the boilers. However, it will be understood that these return openings may be located in any portion of the boiler according to the requirements of the boiler.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

1. The combination in an independent boiler structure, of a hollow boiler unit having oppositely disposed longitudinal extensions spaced apart, a base made of sections, said sections comprising plates provided with extensions detachably connected together and having ledge portions providing a support for said boiler unit, side panels supported by said base and extending longitudinally adjacent the outer edges of said extensions to form flues of the space between said outer extensions, and a hood adjacent the top of said panels and boiler unit, said hood providing a chamber for the products of combustion after passing upwardly through said flues, substantially as described.

2. A hollow boiler unit having hollow extensions disposed at opposite sides and spaced apart, said extensions being arranged comparatively close together and in straight rows to provide separate and independent flues between the extensions, said flues and extensions running from the top to the bottom of the boiler unit, substantially as described.

3. In a boiler structure, the combination

of a plurality of independent boilers, each of said boilers having oppositely disposed longitudinal extensions, said boilers being positioned with certain of the extensions of each boiler adjacent each other, the end ones of said adjacent extensions being designed to form a seal for the spaces between the intervening extensions, side panels adjacent the other of said extensions, and a base for the boilers and side panels, substantially as described.

4. In a boiler structure, the combination of a plurality of independent boilers, a base therefor made of sections, said sections comprising members detachably connected together and providing a ledge for supporting the boilers, said sections having connecting portions designed to receive connecting portions of other side sections whereby the base can be lengthened to provide a support for additional boilers, said boilers having lateral extensions providing flues, panels forming a closure for the outer side flues, and a hood made in detachable sections mounted above said boilers, said sections having registering openings to permit pipes to pass therethrough and connect with said boilers, said hood sections having portions designed to receive connecting portions of other hood sections whereby the hood can be increased in length or cover additional boilers, substantially as described.

5. In a boiler structure, the combination of a plurality of independent boilers, a base therefor made of sections, said sections comprising members detachably connected together and providing a ledge for supporting the boilers, said sections having connecting portions designed to receive connecting portions of other side sections whereby the base can be lengthened to provide a support for additional boilers, said boilers having lateral extensions providing flues, panels forming a closure for the outer side flues, and a hood made in detachable sections mounted above said boilers, said sections having registering openings to permit pipes to pass therethrough and connect with said boilers, said hood sections having portions designed to receive connecting portions of other hood sections whereby the hood can be increased in length or cover additional boilers, substantially as described.

6. In a boiler structure, the combination of a plurality of independent boilers, a base therefor made of sections, said sections comprising members detachably connected together and providing a ledge for supporting the boilers, said boilers having lateral extensions providing flues, and panels forming a closure for the outer side flues, and a hood made in sections and having interengaging lips forming seals for the parting

between said sections, substantially as described.

7. In a boiler structure, the combination of a plurality of independent boilers, a base therefor made of sections, said sections comprising members detachably connected together and providing a ledge for supporting the boilers, said boilers having lateral extensions providing flues, certain of said latter extensions having tongues and grooves therein, the tongues of one boiler engaging the grooves of another boiler to form a seal at the parting between the boilers, substantially as described.
- 15 8. A hollow boiler unit having hollow extensions disposed at opposite sides and spaced apart, said extensions being arranged comparatively close together and in straight rows to provide separate and independent flues between the extensions, said flues and extensions running from the top to the bottom of the boiler unit, certain of the extensions at their ends being provided with ribs and grooves adapted to form a seal with other boiler units, substantially as described.
- 20 9. A plurality of independent boilers each having extensions disposed at opposite sides, said extensions being spaced apart and pro-

viding flues for the products of combustion, the end extensions of each boiler being longer than the intermediate extensions, the end extensions on one side of each boiler having longitudinally extending tongues, the end extensions on the other side of each boiler having longitudinally extending grooves, the tongues of one boiler being designed to fit within the grooves of another boiler to form a flue seal therebetween, substantially as described.

- 25 10. A plurality of independent boilers each having extensions disposed at opposite sides, said extensions being spaced apart and providing flues for the products of combustion, the end extensions of each boiler being longer than the intermediate sections, and means forming a flue seal between adjacent long extensions of said boilers, substantially as described.

In testimony whereof I have signed my name to this specification in the presence of two subscribing witnesses.

WILLIAM KANE.
